UNITED STATES PATENT OFFICE.

WOLF ARBETTER, OF CHELSEA, MASSACHUSETTS, ASSIGNOR TO ARBETTER FELLING MACHINE COMPANY, OF BOSTON, MASSACHUSETTS, A CORPORATION OF MAINE.

BLINDSTITCH-FELLING MACHINE.

1,152,871.

Specification of Letters Patent.

Patented Sept. 7, 1915.

Application filed June 2, 1908. Serial No. 436,223.

To all whom it may concern:

Be it known that I, WOLF ARBETTER, a citizen of the United States, residing at Chelsea, in the county of Suffolk and State

5 of Massachusetts, have invented an Improvement in Blindstitch-Felling Machines, of which the following description, in connection with the accompanying drawing, is a specification, like letters on the drawing 10 representing like parts.

This invention relates to a sewing machine for felling with blind stitches; that is of the general type of machine illustrated 15 in patent to Arbetter No. 830,699, granted September 11, 1906.

The invention is more particularly concerned with the means for feeding the fabric, although it involves in addition other features. In felling work a superimposed 20 layer or layers of material, presenting either a raw or a turned-in edge are fastened to a main or base layer, as in the case of the fastening of the lining of a coat to the main fabric of the coat. The stitches are taken 25 usually alternately in the base layer and in the superimposed layer or layers, and in the latter case the stitches in the superimposed layer or layers generally do not pass into the base layer. The main or base layer of 30 fabric is usually of a different material from the superimposed layer or layers. Often the base layer is of a comparatively rough and thick cloth where the superimposed layer or layers is of a smooth and thin 35 cloth. It is highly desirable and in many cases necessary to secure a satisfactory quality of work that the action of the feeding mechanism upon the superimposed layer or layers shall be different from that upon the 40 base layer.

The present invention provides a feeding mechanism which overcomes the difficulties heretofore existing in many cases to the proper feeding of felling work through the 45 machine. If a fullness exists in the superimposed layer or layers with respect to the base layer, or if it is desired to secure such a fullness in the making of a garment the feeding mechanism of this invention either 50 retains the same or provides therefor. When such fullness is taken care of in an ordinary machine the operator usually retards the feed of the main layer manually and at the same time pushes in beneath the presser-foot 55 the upper layer. This results in a stretching

of the main layer and in the formation of irregular stitches, both of which are undesirable and which are obviated by this invention.

The invention will more fully appear 60 from the accompanying description and drawings, and will be particularly pointed out in the appended claims.

The drawings represent the entire machine in its preferred form embodying the 65 present invention.

Figure 1 is a side elevation of the forward end of the head of the machine, parts thereof being broken away to show certain portions of the mechanism clearly. Fig. 2 is an 70 end elevation of the head of the machine with the face-plate removed. Fig. 3 is a detail in front elevation of a portion of the auxiliary feeding device. Fig. 4 is a top plan view of the parts shown in Fig. 3. Fig. 75 5 is a top plan view of the auxiliary feeding device, its slide, and the portion of the head upon which it is mounted. Fig. 6 is an end elevation of the lever and connected parts for transmitting motion from the shaft of 80 the machine to the auxiliary feeding device. Fig. 7 is a view of the double cam for operating the auxiliary feeding device. Fig. 8 is an end elevation of a portion of the machine 85 showing the position of the auxiliary feed point, the lower feed dog, needle and presser-foot as the needle starts downward, and before the feed of the goods has taken place. Fig. 9 is a view similar to Fig. 8 90 omitting some of the details below the bed-plate with the parts in position after the feed of the goods has taken place and before the needle has entered the fabric. Fig. 10 is a view similar to Fig. 9 with the parts in position with the needle in the fabric to 95 make the stitch and with the lower feed dog preparing to retract. Fig. 11 is a view similar to Fig. 9 with the needle withdrawing from the fabric, with the lower feed retracted preparatory to feeding forward, and 100 with the auxiliary feed point about to move forward. Figs. 12, 13, 14 and 15 are views of the fabric and the point of the auxiliary feeding device showing the position relatively to each other under the conditions 105 illustrated respectively in Figs. 8, 9, 10 and 11. Figs. 16, 17 and 18 are top plan views of the lower portion of the presser-foot and showing the point of the auxiliary feeding device in the position shown in Figs. 8, 10 110

and 11 respectively. Fig. 19 is a top plan view of the lower feed dog. Fig. 20 is a top plan view of the lower feed dog and surrounding bed-plate of the machine and of the bender. Fig. 20^a is a view of a portion of the bottom of the presser-foot. Fig. 21 is a front end elevation of the lower portion of the machine showing the lower feeding and the bender mechanisms. Fig. 22 is a cross-sectional elevation of the lower portion of the machine taken on the line $x-x$, of Fig. 24. Fig. 23 is a cross-sectional elevation of the lower portion of the machine taken on the line $y-y$, Fig. 24. Fig. 24 is a bottom plan view of the machine.

It is unnecessary here to illustrate and describe some of the adjunctive mechanisms of the machine, such for example as the tension and the take-up mechanism, because they are not particularly involved in the present invention and are fully illustrated and described in prior patents, among which may be noted the aforesaid Patent No. 830,699; neither will it be necessary here to explain and describe in detail many of the parts illustrated for the same reason.

In the drawings, A represents the head or forward end of the overhanging arm of the machine provided with a face-plate 30 which is here shown as removed to expose the interior parts, and which is held in position by screws entering the holes a .

In the type of machine illustrated a presser-foot D supported from the presser-foot carrier d^4 by the screw d^6 is rigidly connected to the head A, being adjustable vertically by means of lock-nuts, one of which is shown at 15, all as set forth in said patent.

The work-support E presenting a flat surface beneath the presser-foot projecting slightly above the work-table E² is mounted upon a work-support stand E⁵, which slides vertically in ways E³ and is normally held in its elevated position by the spring E⁴. The work-support is depressed by the lever E⁶, pivoted at E⁷ and engaging a stud E⁸ projecting from the stand E⁵. The lever E⁶ may be operated in any suitable manner and for that purpose a bell-crank lever designed to be operated by the knee is pivotally mounted at E⁹ in the frame of the machine and projects above the end of the lever E⁶.

The main driving shaft A extends horizontally through the head and is provided at its forward end with a pinion C', adjustably connected thereto by set-screws c¹⁰. On the face of the pinion C' is mounted a 60 rotarily adjustable disk B to which is eccentrically connected the needle operating rod B². A grooved cam c⁴ is mounted on a stub-shaft c¹⁴ and driven from the pinion C' by a gear C intermeshing therewith. A 65 vertical rock-shaft B¹⁰, mounted in the

lower portion of the head, carries at its lower end the long transverse bearing B⁸, in which the needle carrying rock-shaft B⁷ is supported. A curved needle a², whose curvature is substantially concentric with the axis of the shaft B⁵, is mounted in the needle carrying arm b', attached to the end of the rock-shaft B⁷. The needle a² is given its oscillating movements to enter and leave the fabric by means of a rocker arm B⁴ 70 connected to the rod B², and it is bodily given oscillations about the axis of the rock-shaft B¹⁰, so as to place the needle in making one set of stitches parallel, and while making another set of stitches inclined to the line of feed, by means of an adjustable connection between the grooved cam c⁴ and the rock-shaft B¹⁰. This connection comprises a short vertical rock-shaft T mounted in a suitable bearing in the head 80 and provided at its lower end adjustably connected thereto by a set-screw t, with a rocker-arm T'. This rocker-arm carries on its upper side a stud T⁵ which rides in the groove of the cam c⁴ and said arm is also slotted longitudinally and a sliding carrier T² is mounted in said slot and adjustable longitudinally therein by means of the set-screw T³. The carrier T² has pivotally mounted thereon a stud T⁴, which enters the slot of the rocker-arm S fast on the rock-shaft B¹⁰.

The details of that portion of the stitch-forming mechanism complementary to the needle need not be described. The position of these parts is indicated by the framework A⁸ supporting the revolving hook a²⁰ so as to rotate in a plane transverse and oblique to the path of reciprocation of the needle and transverse and oblique to the work-support.

The main or lower feeding mechanism is of the four-motion type, and its active elements are mounted in and carried by the work-support stand E⁵, so that the feed-dog will always have its proper relation with respect to the work-support E in what ever position the work-support may occupy during the operation of the machine.

The feed-dog F is suitably secured, as by the screws F², to the horizontal slide F³, horizontally slotted at F⁴ and held in place for horizontal sliding movement in the vertical slide F⁵ by a face-plate F⁶, secured thereto by the screws F⁷. The vertical slide F⁶ is mounted to slide vertically in the work-support stand E⁵, and is held in place therein by the face-plate F⁸ by means of screws F⁹.

The up-and-down or vertical movement is given to the feed-dog by means of the rotary cam acting between the ledges F¹², F¹³, projecting from the back of the vertical slide F⁶. This cam F¹⁰ is carried by a short shaft section G², mounted in the bearing G³ 125 130

in the vertically-movable work-support stand, and consequently the shaft section G^2 partakes of any vertical movement of the work-support stand, and hence the operation of the cam F^{10} is independent of such vertical movement.

The back-and-forth or horizontal feeding movement of the feed-dog is given by means of a long link H , having one end connected 10 at H^2 to a rocker-arm H^3 projecting from the shaft H^4 , and connected at its other end at H^6 to the horizontal slide F^2 . The length of this link H is such that any vertical movement given to the work-support stand will 15 not affect appreciably the horizontal movement of the feed-dog.

Movement is imparted to the shafts G^2 and H^4 for giving the vertical and horizontal movements to the feed-dog from the 20 main driving shaft A of the machine. A vertical shaft at the rear end of the machine is geared to the main shaft A by gearing not necessary to show herein, and carries at its lower end the bevel gear G^4 , intermeshing with the bevel gear G^5 , fast on the shaft section G^6 , journaled in bearings G^7 , G^8 .

The shaft section G^6 is connected by a universal joint to a shaft section G^9 , which 30 in turn is connected by a second universal joint with the shaft section G^2 . The shaft section G^2 is therefore driven directly, and the intermeshing section G^9 allows for the vertical movement of the work-support stand in which the shaft section G^2 is mounted.

The shaft section G^6 carries a cam H^5 which operates one arm H^6 of the bell-crank lever fulcrumed at H^7 , and having its other 40 arm H^8 slotted to receive therein one end H^9 of a lever H^{10} , pivoted at its opposite end H^{12} to a rocker-arm H^{13} , attached to the shaft H^4 . It will thus be seen that the cam H^5 acts to rock the shaft H^4 to give the 45 horizontal movement to the feed-dog, and that this movement may be adjusted by varying the position of the end H^9 of the link in the slot of the arm H^8 . A link H^{14} is shown which can be operated and adjusted 50 in any suitable manner to determine the amount of adjustment of the feed.

The bender is similar in construction and operation to that shown in the above-mentioned patent, and operates upon each movement of the needle to form the stitch in the single or base layer, to project the material into the path of the needle. This bender L is carried by a bender-support L^2 , mounted 55 to slide vertically in bearings L^3 , in the face-plate E^{20} , which is fastened to the work-support stand by suitable screws E^{21} , and serves to retain the vertically-movable work-support stand E^5 in its ways.

The bender is given its vertical movement 60 by means of a stud L^4 , acting between the

projections on the bender-support and carried by a rocker-arm L^5 , mounted on the rock-shaft L^6 , which is provided at its opposite end with the arm L^7 acting against the cam L^8 , carried by the bender-shaft L^9 . 70

The shaft L^9 is driven by two-to-one gearing from the shaft section G^6 so that there is one revolution of the cam L^8 to each two movements of the feed, and consequently the bender has one movement to each two 75 movements of the feed or to each two reciprocations of the needle. The rock-shaft L^6 is provided with a third arm L^{10} , and a strong spring L^{12} adjustable by the set-screw L^{13} connects the end of the arm L^{10} to the frame of the machine. The spring L^{12} acts to raise the bender and the cam L^8 acts to depress it. The bender is hence given one upward reciprocation to each two 80 reciprocations of the needle, and this movement of the bender is given at the time the straight stitch in the main fabric is taken so as to bend the fabric into the path of the needle.

The auxiliary feeding device by means of which the control of the feeding of the upper and lower layers of material is secured, is herein shown as a feeding point P , curved forwardly to catch the upper layer or layers of the material, move them slightly independently of the lower layer, and crowd them slightly beneath the presser-foot and between it and the feed-dog. This feeding point P is given an up-and-down and forward and backward movements by suitable 90 mechanism in proper timing to secure the desired results. This mechanism for operating the feeding point is herein shown as mounted in the overhanging arm and operated directly from the main driving shaft. 95 The feeding point P is carried at the lower end of a vertically-arranged arm P^2 , shaped so as not to interfere with the needle-operating parts. This arm is mounted to slide vertically in the part P^3 which in turn is 100 mounted to slide horizontally in the machine head. The arm P^2 is provided on one face with a vertical fin P^4 by which it is guided in its vertical sliding movement in a corresponding recess in the horizontal slide P^3 , and it is extended laterally and slotted 105 at P^5 to present horizontal edges P^6 , against which the cam P^7 , carried by the stub-shaft P^8 acts to give the desired vertical movement. 110

The horizontal slide P^3 is slotted at each end and guided thereby on studs or projections P^9 of the machine head and held in place thereon by plates P^{10} . The horizontal slide P^3 is retracted by means of the spring 115 P^{12} , and is given its forward movement by the cam P^{13} , acting against the edge P^{14} of an opening formed therein. The cam P^{13} is carried by the same stub-shaft P^8 as the cam P^7 , and these cams are so related to 120

each other and to the shaft P^8 as to secure the required up-and-down and backward-and-forward movements and the proper timing of the feed point.

5 The stub-shaft P^8 extends through the machine head to the rear thereof where it carries a slotted crank-arm P^{15} . The shaft P^8 is rotated by means of a lever P^{16} , slotted at P^{17} to slide and rock on the fulcrum pin P^{18} , and having its lower end provided with a stud P^{19} , engaging the slot of the crank arm P^{15} , while its upper end is formed into an eccentric strap P^{20} , surrounding the eccentric P^{21} . The eccentric P^{21} is integral with or fast to a disk P^{22} , loosely mounted on the main shaft A .

A hub P^{23} is made fast to the shaft A by means of a set screw P^{24} . A clutch-disk P^{25} is keyed at P^{26} to slide upon the hub P^{23} , and is slotted at P^{27} to receive the stud P^{28} in the yoke P^{29} , pivoted at P^{30} to the head. The clutch-disk P^{25} is provided with two pins of different sizes P^{31} , P^{32} , adapted to engage holes of corresponding size in the disk P^{22} . When, therefore, the clutch-disk P^{25} is shifted so that the pins P^{31} and P^{32} engage the holes in the disk P^{22} , the eccentric P^{21} will be rotated with the shaft A , and the auxiliary feeding mechanism will be operated. When for any reason it is desired to throw out of operation the auxiliary feeding mechanism the clutch-disk is shifted to disengage the pins and thus stop the movement of the eccentric P^{21} .

35 In order to retain the auxiliary feeding mechanism when out of operation in elevated position a spring-depressed pin P^{40} is provided which when released is forced downwardly and seats in the recess P^{41} in the top of the eccentric strap P^{20} .

The presser-foot D is of the same general construction as that shown in the aforesaid patent, but arranged to provide for the operation of the auxiliary feeding device. At 45 its heel portion it carries the guide D^2 for the edge of the superimposed layer or layers, and at its toe portion it is provided with a guard-plate D^3 . The needle in making the stitches rubs lightly against the rear portion D^4 of the needle-throat, and the forward portion D^5 of the needle-throat is of sufficient width to allow of the swinging of the needle from the straight to the diagonal stitch. The feeding point acts in line with 50 that portion of the presser-foot which is above the superimposed layer or layers. This portion of the presser-foot has the beveled extension D^{12} which serves to guide the superimposed layers therebeneath. The 55 body portion of that portion of the presser-foot beneath which the feeding point P acts is also beveled for a short distance as shown at D^{13} . This latter beveled portion B^{13} enables the feeding point to push or crowd the 60 superimposed layer or layers of material be-

neath the presser-foot, as already described. The forward movement of the feeding point terminates about at the end of this beveled portion D^{13} .

70 The feed-dog F is provided with the usual serrations, and these are so arranged as to act upon the fabric at all points beneath the presser-foot and insure its being fed forward regularly and evenly. The feed-dog also carries a smooth-faced presser R , herein termed an auxiliary presser foot which is held upwardly by a strong leaf-spring R^2 , fastened at R^3 to the rear end of the feed-dog. This presser presents a surface extending over the entire range of action of the feeding point P , and is adapted to coöperate therewith and hold the work firmly thereagainst, without retarding the work during the operation of the feeding point P . The fact that the presser is made yielding by means of the spring R^2 enables the proper operation of the feed-dog F against the lower surface of the work. If the feeding point in its downward motion coöperated with the feed-dog F alone the result would be to depress the feed-dog and with it the entire vertically-yielding work-support, thus preventing the proper action of the feed-dog upon the lower surface when the feeding movement of the feed-dog occurred. The upper surface of the presser arm is made smooth in order that the feed point when having its movement thereover independent of the movement of the feed-dog shall not injure or mar the fabric.

75 The operation of the machine will be clear from the foregoing, but it may be well here to call attention in particular to the operation of the feeding instrumentalities upon the material in connection with the movements of the needle. The operation will best appear from Figs. 8-20^a of the drawings.

80 In Figs. 8, 12 and 16 the feeding point P is shown at its extreme lower and forward position with its point beneath the beveled portion D^{13} of the presser-foot, holding the superimposed layer slightly bunched up and crowded beneath the presser-foot, the feed-dog F being in its elevated and retracted position ready to begin the forward main feeding movement. The feed-dog F now moves forwardly to give the main feed to the goods until the feed-dog F assumes the position shown in Fig. 9; in its forward movement the feed-dog F carries forward not only the base or main layer of the fabric, but also the upper layers, and at the same time straightens out or removes the fullness caused in the upper layers by the feeding point, thus securing the proper feeding of both layers under the main presser-foot and maintaining the desired relation between the two layers. The feeding point now retracts and moves upwardly to clear itself from the beveled portion D^{13} of the presser-foot, and

130

continues its movement until it reaches its uppermost position, as shown in Figs. 9, 13 and 17; while the feeding point is thus moving upward from beneath the presser-foot 5 the feed-dog completes its forward movement, if necessary, and remains in its upward position until there is no danger of the feeding point disturbing the goods while moving from beneath the presser-foot, al- 10 though the path of retraction of the feeding point P is different from the path which it had in moving beneath the presser-foot, but by the time the feeding point reaches its uppermost position shown in Fig. 9 the feed- 15 dog F is lowered, as shown in Fig. 9, preparatory to having its backward movement. While the parts are in this position as again shown in Figs. 10, 14 and 17, the needle pen- 20 trates the fabric to form the stitch. While the needle is retracting the feeding point P and the feed-dog F move backwardly; and when the needle has withdrawn from the fabric the feeding point P moves downward, and at the same time the feed dog F moves 25 upward, and the parts assume the position shown in Figs. 11, 15 and 18. The feed- 30 point P is now in contact with the upper or superimposed layers and the feed-dog F with the base layer, the presser R being be- neath the feeding point. The feeding point 35 is next moved forward, acting above and against the yielding presser-arm, and slightly pushes or puckers the upper layer and finally crowds it in that condition be- 40 neath the beveled portion D¹² of the presser- foot until the parts assume the position al- ready described, as shown in Figs. 8, 12 and 16.

It will be seen that the auxiliary feeding 45 device, especially when coöperating with the auxiliary presser foot, constitutes a means for compensating for the irregular retarding action of the presser foot upon the upper surface of the goods.

Having described my invention, what I claim as new and desire to secure by Letters Patent, is:

1. A blindstitch sewing machine for fell- 50 ing a superimposed layer or layers of fabric to a base layer, comprising a work-support, a reciprocating needle and complementary stitch-forming mechanism located and operative at one side of said work-support, independent feeding instrumentalities acting 55 upon the opposite faces of the fabric, and means for operating them to give a feeding movement to the upper instrumentality when the lower is substantially at rest, and then to give a feeding movement to the 60 lower instrumentality.

2. A blindstitch sewing machine for fell- 65 ing a superimposed layer or layers of fabric to a base layer, comprising a work-support, a reciprocating needle and complementary stitch-forming mechanism located and oper-

ative at one side of said work-support, a presser-foot coöperating with said work-support to hold the material therebetween, feeding mechanism located on the opposite side of the work-support from the stitch-forming mechanism and operative to feed the material forward at desired intervals, auxiliary feeding mechanism located on the same side of the work-support as the stitch-forming mechanism and operative upon the superimposed layer or layers of fabric only, and means for operating said auxiliary feeding mechanism to cause it to have its feeding movement while the main feeding device is at rest, whereby the superimposed layer or 80 layers will be fed forward slightly independently of the base layer.

3. A blindstitch sewing machine for fell- 85 ing a superimposed layer or layers of fabric to a base layer, comprising a work-support, a reciprocating needle and complementary stitch-forming mechanism located and operative at one side of said work-support, a presser-foot adapted to rest on the upper surface of the fabric, a main feeding device 90 operating against the lower surface of the fabric, an auxiliary feeding device operating against the upper surface of the superimposed layers, an auxiliary presser-foot mounted to yield vertically with respect to 95 the work support and adapted to rest against the lower surface of the fabric beneath the auxiliary feeding device, and means to operate the auxiliary feeding de- 100 vice to cause it to contact with the upper surface of the superimposed layers and move forward relatively to the auxiliary presser-foot and tuck the upper layer under the presser-foot resting upon the upper surface of the fabric.

4. A blind-stitch sewing machine for fell- 105 ing a superimposed layer or layers of fab- 110 ric to a base layer, comprising a work-sup- 115 port, a reciprocating needle and complementary stitch-forming mechanism located and operative at one side of said work-support, a presser-foot and an auxiliary feeding de- 120 vice located on the same side of the work- 125 support as the stitch-forming mechanism, the said auxiliary feeding device adapted to act only on the superimposed layer, a main feeding device and an auxiliary presser-foot carried thereby located on the opposite side of the work-support, means to operate the auxiliary feeding device while the main feeding device is in substantially retracted position to cause it to descend and clamp the fabric against the auxiliary pres- 130 ser-foot, and then to move forward, means for thereafter causing the completion of the feeding movement of the main feeding device.

5. A blindstitch sewing machine for fell- 130 ing a superimposed layer or layers of fab- 135 ric to a base layer, comprising a work-sup-

port, stitch-forming mechanism located and operative at one side of said work-support, a presser-foot adapted to rest upon the upper surface of the fabric, a main feeding device operating against said presser-foot, and means for giving it the usual four motion feeding movement, an auxiliary presser-foot carried by said feeding device, an auxiliary feeding device acting on the upper 10 surface of the superimposed layer or layers and coöperating with said auxiliary presser-foot, means for moving the auxiliary feeding device to cause it to descend upon and clamp the fabric against the auxiliary presser-foot, and to move the upper layers forward upon said auxiliary presser-foot, and crowd them slightly beneath the presser-foot.

6. A blindstitch sewing machine for fell-
20 ing a superimposed layer or layers of fab-
ric to a base layer, comprising a work-sup-
port, a reciprocating needle and comple-
mental stitch-forming mechanism located
and operative at one side of said work-sup-
25 port, a main feeding device located oppo-
site to the stitch-forming mechanism, an
auxiliary feeding device located on the same
side of the work-support as the stitch-form-
ing mechanism, and adapted to only oper-
30 ate on the superimposed layer or layers,
means for giving four motion feeding move-
ments to each of said feeding devices, the
said feeding movements being so arranged
that the first and main portion of the for-
35 ward feeding movement of the auxiliary
feeding device occurs while the main feed-
ing device is retracted and substantially at
rest.

7. A blindstitch sewing machine for fell-
40 ing a superimposed layer or layers of fab-
ric to a base layer, comprising a work-sup-
port, stitch-forming mechanism located and
operative at one side of said work-support,
a presser-foot mounted upon the same side
45 as, and a main feeding device mounted on
the opposite side of the work-support from,
the stitch-forming mechanism, a spring-

pressed auxiliary presser-foot mounted in
and carried by the feed dog of the main
feeding device, an auxiliary feeding device 50
operating with said auxiliary presser-foot,
and means for operating it independently of
the main feeding device.

8. A blindstitch sewing machine for fell-
ing a superimposed layer or layers of fabric 55
to a base layer, comprising a vertically yield-
ing work-support stand, a lower feed dog
mounted in and carried by said stand, means
for giving feeding movements to the feed
dog independently of the stand, and a lower 60
presser foot mounted in, carried by, and
vertically yielding with respect to, said feed
dog.

9. A blindstitch sewing machine for fell-
ing a superimposed layer or layers of fabric 65
to a base layer, comprising independent
feeding instrumentalities acting upon the
opposite faces of the fabric, means for oper-
ating them independently, means for sus-
pended the operation of the upper instru-
70
mentality.

10. A blindstitch sewing machine for fell-
ing a superimposed layer or layers of fabric
to a base layer, comprising independent 75
feeding instrumentalities acting upon the
opposite faces of the fabric, means for oper-
ating them independently, means for sus-
pended the operation of the upper instru-
70
mentality, and means for locking the upper
feeding mechanism in fixed position when
suspended.

11. A sewing machine, comprising a work-
support, a feed dog mounted therein, means
for giving the feed dog feeding movement
relative to the work-support, a presser foot
85
mounted in, carried by, and vertically yield-
ing with respect to, said feed dog.

In testimony whereof, I have signed my
name to this specification, in the presence
of two subscribing witnesses.

WOLF ARBETTER.

Witnesses:

MABEL PARTELOW,
THOMAS J. DRUMMOND.
